UNITED STATES PATENT OFFICE.

JAMES HENRY GRIMES, OF PADUCAH, KENTUCKY.

SEWING CABINET.

Application filed October 7, 1927. Serial No. 224,623.

The invention aims to provide a simple, compact and very desirable sewing cabinet which may be used to contain all necessary equipment for hand sewing, novel provision being made for supporting a plurality of spools of thread so that any desired thread is readily accessible for use.

With the foregoing in view, the invention resides in the novel subject matter herein-
10 after described and claimed, the description being supplemented by the accompanying drawing.

Fig. 1 is a perspective view showing the doors of the cabinet closed.

15 Fig. 2 is a vertical transverse section on line 2—2 of Fig. 1.

Fig. 3 is a perspective view showing the cabinet doors opened.

20 Fig. 4 is a longitudinal section on line 4—4 of Fig. 3.

Fig. 5 is a fragmentary perspective view showing the manner of releasably supporting one end of the pins which carry the spools of thread.

25 In the drawings above briefly described, the numeral 6 designates a preferably shallow container divided by a longitudinal partition 7, into a pair of compartments 8 for sewing equipment, said compartments being provided with hinged doors 9 at their tops and containing any desired racks or the like 10 for holding shears, needles, thimbles, etc.

35 Four posts 11 are secured to and rise from the partition 7, said posts being spaced apart longitudinally of the device. The two innermost posts are connected at their upper ends by a carrying handle 12 and novel provision is made between these inner posts and the outer posts, for supporting a plurality of spools of thread 13. The supporting means for all spools is identical and may be duplicated at any desired number of places, and a description of the supporting means for 45 one spool will therefore suffice.

14 denotes a pin having an eye 15 at one end inter-engaged with another eye 16 carried by the inner side of one of the posts 11, said eye 16 being preferably an ordinary 50 screw eye threaded into the post. 17 denotes a U-shaped support for the other end of the pin 14, said support being preferably formed from another screw eye threaded into the in-

ner side of one of the posts 11, the eye proper being bent flat against this post and opened to provide the desired U-shaped formation, into and from which the free end of the pin 14 may be readily moved. By disengaging this end of the pin 14 from the support 17, a spool 13 may be easily applied to or removed from said pin, as occasion may demand.

Preferably, the posts 11 are disposed in pairs, one pair being near one end of the base or receptacle 6, while the other pair is near the other end thereof. The posts of these pairs need be spaced only sufficiently to receive the spools 13 and their supporting means, but the innermost posts of the two pairs are preferably spaced further apart in order that the handle 12 may be of greater length than would otherwise be possible.

It will be seen from the foregoing that I have provided a very simple and inexpensive sewing cabinet, yet one which will be very 75 convenient, will permit quick location of any sewing equipment necessary, will always hold spools of thread at readily accessible positions, will easily permit unwinding of any desired length of thread, and will readily permit empty spools to be removed and new ones to be substituted.

Such desirable results have been obtained from the details disclosed that they are preferably followed. However, within the scope 85 of the invention as claimed, variations may be made.

I claim:

1. A sewing cabinet comprising a receptacle for sewing equipment, four posts secured to and rising from a rigid part of said receptacle, a carrying handle extending between and connected with the innermost of said posts, and spool-supporting means between and supported by said innermost and the outermost posts.

2. In a sewing cabinet, two spaced posts, a horizontal pin having a permanent swivelled connection with the inner side of one of said posts whereby said pin may be swung around to different angles, and a flat U-shaped seat on the inner side of the other post, said seat removably receiving the free end of said pin.

In testimony whereof I have hereunto affixed my signature.

JAMES HENRY GRIMES.
